UNITED STATES PATENT OFFICE.

GEORGE ANDERSON MOORE AND HARRY J. ROSEGRANT, OF PHILADELPHIA,
PENNSYLVANIA.

SOLE-LAYING MACHINE.

SPECIFICATION forming part of Letters Patent No. 606,176, dated June 21, 1898.

Application filed May 26, 1897. Serial No. 638,318. (No model.)

To all whom it may concern:

Be it known that we, GEORGE ANDERSON MOORE and HARRY J. ROSEGRANT, citizens of the United States, residing at Philadelphia, in the State of Pennsylvania, have invented a new and useful Sole-Laying Machine, of which the following is a specification.

Our invention relates to the manufacture of boots and shoes, and has for its object a machine which takes the boot or shoe after the outside sole has been laid upon and cemented to the inner sole or filling and welt and by means of a milled roll in combination with a superposed lip smoothly presses and sets together the said welt and the edge of the said outside sole.

We attain our object by the mechanism illustrated in the accompanying drawings, in which—

20 Figure 1 is a side elevation of our machine, part of which is shown in vertical section; and Fig. 2 is a sectional view of a shoe in position when the operation is performed.

In the drawings, A is a pedestal carrying 25 the frame B, composed of a base attached to said pedestal and two upright pillars. Said pillars constitute the bearings for the shaft D. Said shaft is driven by the gear-wheels C at one end, while at the other end it is furnished with the milled roll E, set upon it by 30 collar and set-screw, and which roll forms a support for the shoe and extends outwardly beyond the outer end of the lip. One of the said pillars B' is hollowed to receive the 35 tension-spring H, (shown at G,) which, by means of the thumb-screw J, permits the journal I to be adjusted as desired, so that the said milled roll E may have a close or loose contact with the lip F, which is rigidly 40 affixed to the pillar B', the outer end of the lip being flat on its under side and tapered on its outer edge, so as to fit in the crease between the welt and the upper. The pressure of this flat surface on the roller causes 45 the wrinkles in the welt to be always straightened out, which is not the case where two rolling surfaces are used.

M is a loose collar carried upon the shaft D, said collar being connected with the treadle L by means of the rod K.

N is the upper of a boot or shoe; P, the insole; O, the welt, and Q the outside sole.

In operation after the outside sole Q is placed upon and cemented to the insole P and the welt O the shoe is delivered to the operator of our machine, who by means of the treadle L separates the milled roll E and the lip F sufficiently to allow the entrance of the welt O and the outside sole Q. He then releases the treadle, and the said roll and lip, 55 with the material between them, come close together. He then passes the shoe around the machine, commencing at the heel and carrying it forward to the toe and back on the other side to the heel again, and the operation is complete. The result of the operation is that the edges of the said welt and outside sole are smoothly and firmly set together and finished ready to go to the next machine for trimming and channeling.

The last is not at any stage of the operation removed from the shoe.

Having now described our invention and the method of its operation, what we claim as new, and desire Letters Patent for, is—

In a machine for pressing the welt against the outer edge of the sole, a rigid lip that is secured to the frame, combined with a vertically-adjustable roller placed upon a driven shaft and which roller projects beyond the outer end of the lip, and forms a support for the sole of the shoe; the outer end of the lip being formed so as to enter the crease between the upper and the welt, and flat on its under side so as to straighten out the wrinkles in the welt, substantially as shown.

GEORGE ANDERSON MOORE.
HARRY J. ROSEGRANT.
